UNITED STATES PATENT OFFICE.

WILLIAM GRAY, OF HARTFORD, CONNECTICUT, ASSIGNOR OF ONE-HALF TO
CHARLES SOBY, OF SAME PLACE.

COIN-CONTROLLED APPARATUS FOR TELEPHONES.

SPECIFICATION forming part of Letters Patent No. 426,266, dated April 22, 1890.

Application filed August 12, 1889. Serial No. 320,449. (No model.)

To all whom it may concern:

Be it known that I, WILLIAM GRAY, of Hartford, in the county of Hartford and State of Connecticut, have invented certain new and useful Improvements in Coin-Controlled Apparatus for Telephones, of which the following is a full, clear, and exact description, whereby any one skilled in the art can make and use the same.

10 The object of my invention is to provide a telephone apparatus, that usually consists of the telephone, magneto-bell, and transmitter, with means of enabling any one who wishes to use the telephone to call the central office in the usual manner, and at the same time enable the operator at the central office to learn whether the fee or toll required for the use of the telephone has been paid before the connection asked for is made, and thus to 20 control and compel the payment of the fee or toll before the connections desired are made.

To this end my invention consists in the novel construction and combination of parts, as will be hereinafter fully described, and especially as the same is particularly pointed out and distinctly claimed.

Referring to the drawings, Figure 1 is a side view of a set of telephone-instruments with 30 part of the signal-box broken away to show construction. Fig. 2 is a detail view of the back board, showing part of the mechanism. Fig. 3 is a detail view in vertical section through the signal-box on plane α α of Fig. 1. Fig. 4 is a detail side view of the signal-locking lever. Fig. 5 is a detail top view of the slide-rod and on enlarged scale. Fig. 6 is a detail view, on enlarged scale, of the lower end of the coin-channels of the tumbler, and 40 of the locking-levers, illustrating the operation of the device.

In the accompanying drawings, the letter a denotes a set of telephone-instruments, b the back board, c the magneto-bell, d the telephone, e the transmitter, and f the battery-box, that are of the usual form and construction and joined up in any ordinary manner for use. In addition to these usual parts

there is provided a signal device g , that in the form shown in the drawings consists 50 of the bells g' g'' , that are located for convenience in a signal-box g^3 , arranged on top of the battery-box. The top of this signal-box has an opening, along the front edge of which is arranged a sound-deflector h , 55 adapted to reflect the sound of the signal device more directly against the diaphragm of the transmitter. The hammer i of the bell, that in the drawings is the common form of gong-bell having a push-button, is held 60 against a striking movement by the arm j' of the signal-locking lever j , that is pivotally supported on the back board and is held in a normal position between a spring j'' and the stop j^3 . The lower end of the lever j is 65 rounded and is arranged in the path of movement of one end of the tumbler k . This tumbler is held in a substantially horizontal position, preferably by gravity, with its end k' projecting either into a coin-channel or across 70 its lower end in such manner as to prevent the passage of a coin out of the channel until the tumbler has been tilted out of the way. The tumbler has a certain play between its normal horizontal position and the point 75 where it engages the arm of the locking-lever. The tumbler has a cam k'' , that, when the tumbler has been tilted a short distance by the weight of a coin, lies in the path of movement of a pin or like projection on a slide- 80 rod l . This slide-rod is mounted in bearings l' , and is held in this forward position by means of a spring l'' , that thrusts against one of the bearings at one end and against a collar l^3 , that is secured to the rod. This collar 85 serves as a stop to limit the forward movement of the rod by coming in contact with one of the bearings. Opposite the outer end of the rod there is preferably secured a stop l^4 , that limits the backward movement of the 90 rod, that has a limited sliding play between the end stop and that formed by the collar and bearing. Except when the tumbler has received an initial movement from a coin the motion of the slide-rod does not affect the 95 tumbler nor the signal-locking mechanism;

but as soon as the cam on the tumbler is moved into the path of a pin or lug *m* on the slide-rod *l* the tumbler is thrown far enough by this movement of the slide-rod to bring the 5 tumbler into contact with the lower end of the locking-lever in such manner as to throw the latter to one side a sufficient distance to unlock the signal device. In this instance it is the hammer of the bell that is liberated by 10 the sidewise movement of the arm *j'* of the locking-lever.

The slide-rod *l* is operated from the outside of the box by means of the arm-rest *n*, that is pivotally supported on the back board and 15 has an arm *n'*, that projects toward and engages the slide-rod. This is preferably operated by placing the elbow on the pad *n''* and pushing downward after having placed a coin in the coin-channel *o*, and by this means giving 20 an initial movement to the tumbler.

My invention may be embodied as illustrated in the apparatus shown in the drawings and hereinbefore described when a bell is used as a signal device; but it is obvious 25 that any sound-producing device may be used in place of the bell with precisely the same result, provided such signal device can be located and locked so as to prevent its use except when released.

30 The object of providing more than one signal device and coin-controlled signal-locking device is to arrange the apparatus so that two or more different tolls may be paid. For instance, the charge for the use of the telephone 35 within a certain circuit may be ten cents, in which instance one coin-channel and a signal of a certain kind or tone will be used in connection with it, while for a larger or more extended circuit a toll of twenty-five cents may 40 be charged, in which case a separate coin-channel, signal device, and signal-locking mechanism is provided, the signal being either different in kind or different in tone from that provided for the other toll. In case a third 45 amount is required as toll it may be fixed as the sum of the other two, in which case coins can be introduced in both channels and both signals sounded, so as to inform the operator at the central office that the tolls have been 50 paid.

My invention is obviously not limited to any particular form or kind of signal device nor any special form of signal-locking mechanism nor precise combination of parts in the 55 coin-operated mechanism, as other and equivalent mechanism and means may be combined and employed in a similar manner for producing the same result.

The method of using my improved apparatus is as follows: A person wishing to use 60 the telephone calls the central office in the usual manner, talks with the operator, and asks that a certain connection may be made. The operator at the central office asks the 65 user of the telephone to drop a coin into the

proper channel and then push down with his elbow on the arm-rest, and then to strike the signal that has been released by this means, and the striking of such signal notifies the operator that the toll has been paid. This 70 enables the would-be user of the telephone to ascertain whether he can communicate with the person or station required before he pays any toll for the use of the wire. As soon as the user lifts his arm the slide-rod is 75 thrown forward by the spring, lifting the arm-rest and at the same time allowing the tumblers to drop into such position that the cam borne on the tumbler is out of the path of movement of the pin on the rod. This sets the 80 device so that the signal device is at once locked and cannot be released except by the payment of another toll.

It is obvious that in the practice of my invention there may be used one or as many 85 more as may be needed of the coin-channels adapted for coins of different sizes, each of such channels being appurtenant to a signal-locking device and a signal device.

No claim is made in this application for 90 these means and combinations thereof, as the same form the subject-matter of another pending application for Letters Patent by me, being Serial No. 334,347, filed December 20, 1889.

95 I claim as my invention—

1. In combination with a telephone apparatus, a signal device, a lever having an arm interposed between the signal and its tappet, and coin-controlled levers for moving the interposed arm from between the signal and the tappet, substantially as and for the purpose specified.

2. In combination with a telephone apparatus, a signal device normally locked, the locking-lever, the tumbler adapted to engage the arm of the lever and with one end projecting into or across the coin-channel, the coin-channel, and the means for tilting the tumbler and holding it temporarily in a fixed 110 position, all substantially as described.

3. In combination with a transmitter of a telephone apparatus, a signal device located adjacent to the transmitter, the signal-locking lever, the tumbler with one end projecting 115 into a coin-channel, the coin-channel, and the tumbler-retaining device, all substantially to described.

4. In combination with the transmitter *e* of a telephone apparatus, the signal device *g*, located adjacent to the transmitter and the sound-deflector *h*, the signal-locking mechanism, and the coin-controlled device for releasing the signal, all substantially as described.

5. In combination with a telephone apparatus, the signal-bell *g'*, having a hammer *i*, the signal-locking lever *j*, with the arm *j'*, normally located in the path of movement of the hammer in striking, and also having an 130

arm j' , located in the path of movement of a tumbler k , the tumbler k , having a cam k'' , normally out of the path of movement of a tumbler-operating slide, and having also a part projecting into the path of movement of a coin, the coin-channel, and a slide rod having a projecting pin adapted to engage the cam on the tumbler, and the lever or like

means for moving the slide-rod and retaining it in its backward position, all substantially as described.

WILLIAM GRAY.
